EX

OR D 11,879

No. 11,879

July 20, 1880

UNITED STATES PATENT OFFICE.

H. CLAY BASCOM, OF TROY, AND TOBIAS S. HEISTER, OF LANSINGBURG, NEW YORK, ASSIGNEES TO OTIS G. CLARK AND DANIEL D. BUCKLIN, EXECUTORS OF THE LAST WILL OF N. S. VEDDER, DECEASED.

DESIGN FOR A COOKING-STOVE.

SPECIFICATION forming part of Design No. 11,879, dated July 20, 1880.

Application filed June 14, 1880. Term of patent 3½ years.

To all whom it may concern:

Be it known that we, H. CLAY BASCOM, of the city of Troy, in the county of Rensselaer and State of New York, and TOBIAS S. HEISTER, of the village of Lansingburg, in said county and State, have jointly invented and produced a new and original Design for Cooking-Stoves, of which the following is a specification, reference being had by letters to the accompanying cut, print, or engraving of a cooking-stove having our said new design.

One part of our invention is the design for the compound panel ornament A, composed of the central bouquet representation, *b*, surrounded by the frame *c*, having the side cornucopia representations, *d*, and top ornaments, *e e'*, all shaped and arranged together as represented in the aforesaid print.

Another part is the design for the panel border F of the oven-door, the same consisting of the raised frame *g*, having angular corner parts, *h*, with the compound in-cut ornaments *h'* therein, and inwardly-projecting ornaments *i*, and the intermediate bar-like portions, *j*, with in-cut lines *k*, and having the middle parts, *l*, and cruciform ornaments *l'* therein, all shaped and arranged together as shown in the aforesaid engraving.

A further part is the design for the oven-door M, consisting of the compound ornamental border F, compound central ornament, A, and intervening surface N, all composed, shaped, and arranged as represented in the aforesaid cut.

35 Another part is the design for the side doors,

O and P, consisting of the central ornament, Q, having the inner ornamental surface, *r*, and raised border *s*, composed of the straight parts *t*, parts *t'*, curved concavely outward and convexly inward, and projecting parts *t''*, the panel-surface U, and the panel-border V, having the in-cut corner ornaments, *w*, all shaped and arranged as shown in the aforesaid engraving.

What we claim as our joint invention is— 45

1. The design for the compound panel ornament A, composed of the parts *b*, *c*, *d*, and *e e'*, all shaped and arranged as shown and described.

2. The design for the panel-border F, consisting of the parts *g*, *h h'*, *i*, *j*, *k*, *l l'*, all shaped and arranged as shown and described. 50

3. The design for the oven-door M, composed of the compound central ornament, A, compound ornamental border F, and intervening surface N, as described and shown. 55

4. The design for the side doors, O P, composed of the central ornament, Q, having the parts *r s t t' t''*, the border V, having the ornaments *w*, and the intermediate surface, U, all shaped and arranged as shown and described. 60

In testimony whereof we hereunto set our hands, in the presence of two subscribing witnesses, this 9th day of June, 1880.

H. CLAY BASCOM.
TOBIAS S. HEISTER.

Witnesses:

JAMES A. GILMAN,
CHESTER BASCOM.
